[57] CLAIM

The ornamental design for a bakery container or the like, as shown and described.

DESCRIPTION

FIG. 1 is a top perspective view of a bakery container or the like showing our new design;

FIG. 2 is a top plan view;

FIG. 3 is a right side elevational view;

FIG. 4 is a front elevational view;

FIG. 5 is a rear elevational view;

FIG. 6 is an enlarged scale fragmentary cross-sectional view taken along line 6—6 of FIG. 2;

FIG. 7 is an enlarged scale fragmentary view taken along line 7—7 of FIG. 3;

FIG. 8 is an enlarged scale fragmentary cross-sectional view taken along line 8—8 of FIG. 3;

FIG. 9 is an enlarged scale fragmentary cross-sectional view taken along line 9—9 of FIG. 3;

FIG. 10 is an enlarged scale fragmentary cross-sectional view taken along line 10—10 of FIG. 4;

FIG. 11 is an enlarged scale fragmentary cross-sectional view taken along line 11—11 of FIG. 4; and

FIG. 12 is an enlarged scale fragmentary cross-sectional view taken along line 12—12 of FIG. 5.
